UNITED STATES PATENT OFFICE.

JOHN OGDEN, OF PHILADELPHIA, PENNSYLVANIA, ASSIGNOR TO OGDEN ELECTRO METALS RECOVERY COMPANY, A CORPORATION OF DELAWARE.

ELECTRO-AMALGAMATING MACHINE.

1,202,006.

Specification of Letters Patent. Patented Oct. 17, 1916.

Application filed March 14, 1916. Serial No. 84,100.

To all whom it may concern:

Be it known that I, JOHN OGDEN, a citizen of the United States, residing at Philadelphia, in the county of Philadelphia and 5 State of Pennsylvania, have invented certain new and useful Improvements in Electro-Amalgamating Machines, of which the following is a specification.

My invention relates to improvements in 10 electro-amalgamating machines, an object of the invention being to provide an improved construction and arrangement of rotary anodes movable through the bath and located at the desired angle to prevent a too 15 great agitation and to reduce resistance of movement to a minimum.

A further object is to provide an improved construction and arrangement of stationary cathode consisting of a cone, preferably of 20 copper or other suitable metal, having an annular gutter containing mercury, and having an extended mercury coated amalgamating surface which is kept clear of accumulating mud or dirt by rotary anodes.

25 A further object is to provide an amalgamating machine in which the pulp is kept in circulation from the bottom of the tank again into the top of the tank, so that the operation is repeated until all the gold or 30 other precious metal has been recovered.

With these and other objects in view, the invention consists in certain novel features of construction and combinations and arrangements of parts as will be more fully 35 hereinafter described and pointed out in the claims.

In the accompanying drawings: Figure 1 is a view in vertical section illustrating my improvements. Fig. 2 is a view in section 40 on the line 2—2 of Fig. 1, and Fig. 3 is a view in section on the line 3—3 of Fig. 1.

1 represents a tank which has a tapering bottom 2, having an outlet pipe 3 at the lower end thereof with a drain cock 4 located 45 in said outlet pipe.

5 is a return pipe having a pump 5^a between its ends, and this return pipe is connected to the outlet pipe 3 above the drain cock 4, and at its upper end discharges into 50 the tank 1, so that the pulp can be returned to the top of the tank as often as it is desired to effect the complete recovery of the gold.

6 represents a conical cathode which is 55 preferably, although not necessarily, of cop-

per having an annular gutter 7 containing mercury 8.

The cathode 6 has a surface coating 9 also of mercury, which presents an extended amalgamating surface, and the gutter 7 with 60 its mercury 8, acts as a trap over which the particles must move, and hence insure a contact of the gold with the mercury. The cathode 6 is removably supported on an annular internal flange 10, having openings 65 11 therein, through which the pulp flows to the bottom of the tank. Cathode 6 is removable, so that it can be removed from time to time with its precious metal. A vertical shaft 12 is supported centrally in tank 70 1, and projects through a bearing 13 in a spider 14, the latter secured in the top of the tank as shown. A series of angularly disposed anodes 15 are supported by shaft 12, and project from opposite sides of the 75 shaft. All of these inclined anodes 15 are constructed alike, and the description hereinafter of one will apply alike to all.

Each anode 15 preferably comprises two or more graphite plates 16, although any 80 other form of carbon plate might be used. These plates 16 are secured to a frame 17, and the latter has a trunnion 18 at one end which projects into a recess 19 in a collar 20 on shaft 12. The trunnion 18 may be 85 turned at any desired angle in the recess 19, and secured at such angle by a set screw 21, so that the angular disposition of each anode can be varied to suit conditions. The lowest pair of anodes 22 are preferably rigidly 90 secured to a collar 23 on the shaft 12, and the lower edges 24 of these lower anodes 22 are beveled or inclined, so that they are located parallel to the surface of the conical cathode 9, and operate to prevent any accumulation of ore, mud, etc., on the surface 95 of the cathode.

25 represents a distributor which is of general conical shape having openings 26 in its central portion, and into this distributor the 100 pipe 5 discharges the returning pulp, and the distributor operates to move the pulp toward the center of the tank, so that it will move downwardly onto the apex of the conical cathode 6.

The shaft 12 has a swiveled electrical connection 27, constituting the positive pole of an electric circuit, and the minus pole of said circuit consists of a contact 28 which projects through a sleeve 29 of insulation, said 110

sleeve located in the wall of tank 1, so that the contact 28 engages the cathode 6. Shaft 12 may, of course, be turned in any approved manner, and I have illustrated a pulley 30 on the upper end of the shaft turned by means of a belt 31.

It is to be understood, of course, that in connection with my improved machine, I may carry out various processes, but a preferred operation is to mix with the ground ore and water, chlorid of sodium and bichlorid of mercury or other suitable re-agents to form an electrolyte.

The passage of the current through the electrolyte from the anodes to the cathodes will compel a deposit of the gold on the cathode, and by reason of the shape of the cathode, the pulp will be subjected to an extended amalgamating surface, and an effective operation will be assured. The pulp will be returned from the bottom of the tank to the top of the tank, and the operation continued until all of the gold is recovered. The cathode 6 will be silver plated or covered with mercury, and the gutter 7 will contain a sufficient amount of mercury to insure a proper amalgamating operation.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. In an electro-amalgamating machine, the combination with a tank, of a conical cathode in the lower portion of the tank, and anodes in the upper portion of said tank above said conical cathode, and means for circulating ore solution between the anodes and cathode, substantially as described.

2. In an electro-amalgamating machine, the combination with a tank, of a cathode in the lower portion of the tank, and anode plates rotatable in paths above said cathode, said plates being inclined to the axis of rotation, substantially as described.

3. In an electro-amalgamating machine, the combination with a tank, of a conical cathode, a rotary shaft in the tank above said cathode, anode plates carried by the shaft, and means for securing said anode plates at an angle to the shaft to intercept material passing downwardly through said tank, substantially as described.

4. In an electro-amalgamating machine, the combination with a tank, of a conical cathode in the lower portion of the tank, a series of rotary anodes in the tank and positioned above the cathode, certain of said anodes having a portion substantially par-

allel with and adapted to prevent accumulation of material on the surface of the cathode, substantially as described.

5. In an electro-amalgamating machine, the combination with a tank, a conical cathode in the lower portion of the tank, rotary anodes in the upper portion of the tank, and means for returning the pulp from the bottom of the tank to the top thereof, substantially as described. 76

6. In an electro-amalgamating machine, the combination with a tank, of a conical cathode supported in the tank, a shaft centrally mounted in the tank, and anodes positioned above said cathode and secured to turn with the shaft, substantially as described. 80

7. In an electro-amalgamating machine, the combination with a tank, of a conical cathode supported in the tank, a shaft centrally mounted in the tank, anodes positioned above said cathode and secured to turn with the shaft, the lowest of said anodes having their edges located parallel to the surface of the cathode, substantially 90 as described. 85

8. In an electro-amalgamating machine, the combination with a tank, of a conical cathode supported in the tank, a shaft centrally mounted in the tank, anodes positioned above said cathode and secured to turn with the shaft, means for conveying the pulp from the bottom of the tank to the top thereof, and a distributer secured on the shaft and into which the returned pulp 100 is directed, substantially as described. 95

9. In an electro-amalgamating machine, the combination with a tank having an internal annular perforated flange near its bottom, of a conical cathode having its base 105 supported on said flange, and rotary anodes in the tank above the cathode, substantially as described.

10. In an electro-amalgamating machine, the combination with a tank having an internal annular perforated flange near its bottom, of a conical cathode supported on said flange, a shaft supported centrally in the tank, and a plurality of annularly positioned anodes supported on the shaft and moved thereby, said anodes being positioned above said conical cathode, substantially as described. 115

11. In an electro-amalgamating machine, the combination with a tank, of a conical cathode in the tank, a central shaft in the tank, anodes secured on said shaft above said cathode, means for turning the shaft, and means for compelling a circulation of pulp through the tank past the anodes and 120 cathode, substantially as described.

12. In an electro-amalgamating machine, the combination with a tank, of a conical cathode in the tank, a central shaft in the tank, anodes secured on said shaft above 125

said cathode, means for turning the shaft, an outlet pipe in the bottom of the tank having an outlet cock therein, a return pipe communicating with the outlet pipe between 5 the cock and the tank, and at its upper end discharging into the upper end of the tank, and a pump located between the ends of the return pipe, substantially as described.

13. In an electro-amalgamating machine, 10 the combination with a tank, of a conical cathode supported within said tank, an upright member, means for moving said member relatively to the cathode, a plurality of anode plates carried by said member, substantially 15 as described.

14. In an electro-amalgamating machine, the combination with a tank, of a conical cathode supported within said tank, an upright shaft, a plurality of anode plates 20 above said cathode and carried by said shaft, means for rotating said shaft, said plates being disposed at an angle to intercept material passing downwardly through said tank in its direction toward said cathode, substantially as described.

15. In an electro-amalgamating machine, the combination with a tank, of a cathode in said tank having its entire uppermost surface inclined, and a plurality of anodes 30 positioned above said cathode, said cathode being positioned below said anodes, substantially as described.

16. In an electro-amalgamating machine, the combination with a cylindrical tank, of 35 a conical cathode positioned within said tank with its apex extending upwardly, said base of the conical cathode being of less diameter than the internal diameter of the tank, said tank having a portion extending 40 below the base of the cathode whereby material may fall through the space between the base of said cathode and the tank, and anodes positioned above said cathode, and means for circulating ore solution between 45 the anodes and cathode, substantially as described.

17. In an electro-amalgamating machine, the combination with a cylindrical tank, of a conical cathode positioned within said tank with its apex extending upwardly, said 50 base of the conical cathode being of less diameter than the internal diameter of the tank, said tank having a portion extending below the base of the cathode whereby material may fall through the space between 55 the base of said cathode and the tank, an upright shaft supported in said tank in substantial alinement with the axis of said conical cathode, anodes carried by said shaft, and means for rotating said shaft, 60 substantially as described.

18. In an electro-amalgamating machine, the combination with a cylindrical tank, of a conical cathode positioned within said tank with its apex extending upwardly, said 65 base of the conical cathode being of less diameter than the internal diameter of the tank, said tank having a portion extending below the base of the cathode whereby material may fall through the space between 70 the base of said cathode and the tank, an upright shaft supported in said tank in substantial alinement with the axis of said conical cathode, anode plates radially disposed with respect to and carried by said 75 shaft, and means for rotating said shaft, substantially as described.

19. In an electro-amalgamating machine, the combination of a tank, a conical cathode positioned within said tank and having an 80 annular gutter, a plurality of anodes positioned above said cathode, and means for circulating ore solution between the anodes and cathode, substantially as described.

In testimony whereof I have signed my 85 name to this specification in the presence of two subscribing witnesses.

JOHN OGDEN.
